ANTENNA AND WIRELESS
COMMUNICATIONS ASSEMBLY

FIELD

The specification relates generally to wireless communications, and specifically to an antenna assembly and associated wireless communication assembly.

BACKGROUND

Printed wireless antennas are employed in a variety of applications, including mobile computing devices (e.g. smart phones) and wireless adapters connectable to computing devices (e.g. desktop computers, "smart" televisions and the like) to enable wireless communication with those devices. Patch elements are common in such antennas; a conventional approach employed to increase the gain or frequency response of a wireless antenna is to replace a single patch (or indeed other types of antenna element) with an array of patches.

Arrays of antenna elements, however, require complex networks of feed lines. In addition to the increased complexity—and therefore cost—of manufacturing such feed line networks, the feed lines can also result in undesirable interference (e.g. due to mutual coupling between the feed lines and the antenna elements), and in undesirably reduced impedance bandwidth. These difficulties are particularly severe at higher frequencies, such as those employed by the IEEE 802.11ad wireless communications standard (also referred to as WiGig™), which prescribes channels having frequencies of about 58 GHz, 60 GHz, 62 GHz and 64 GHz.

SUMMARY

According to an aspect of the specification, an antenna assembly is provided, including a support member having opposing first and second surfaces, and a set of electrical contacts; an antenna carried on the first surface of the support member and electrically connected to the set of electrical contacts; a conductive inner ring element carried on the first surface and surrounding the antenna; and a dielectric outer ring element mounted on the first surface and surrounding the conductive inner ring.

BRIEF DESCRIPTIONS OF THE DRAWINGS

Embodiments are described with reference to the following figures, in which:

FIG. 1 depicts a top isometric view of an antenna assembly, according to a non-limiting embodiment;

FIG. 2 depicts a bottom isometric view of the antenna assembly of FIG. 1, according to a non-limiting embodiment;

FIG. 3 depicts a top plan view of the antenna assembly of FIG. 1, according to a non-limiting embodiment;

FIG. 4A depicts a cross-sectional view of a wireless communications assembly, according to a non-limiting embodiment;

FIG. 4B depicts a cross-sectional view of a wireless communications assembly, according to another non-limiting embodiment;

FIG. 5A depicts a partial isometric view of the wireless communications assembly of FIG. 4A, according to a non-limiting embodiment;

FIG. 5B depicts a partial isometric view of the wireless communications assembly of FIG. 4B, according to a non-limiting embodiment;

FIG. 6A depicts the gain of the antenna assembly of FIG. 1 compared to that of a conventional parasitic patch antenna; and

FIG. 6B depicts the mutual coupling performance of the antenna assembly of FIG. 1 compared to that of a conventional parasitic patch antenna.

DETAILED DESCRIPTION OF THE
EMBODIMENTS

FIGS. 1, 2, and 3 depict an antenna assembly 100 for a wireless communications assembly to be discussed in greater detail below. In general, antenna assembly 100 enables a computing device connected to the wireless communications assembly to exchange data with other computing devices. Such data exchange may be conducted over a variety of communication protocols. In the present embodiment, antenna assembly 100 and the associated wireless communications assemblies discussed later are configured to enable communication using the IEEE 802.11ad standard, and thus transmit and receive data are around 60 GHz.

Antenna assembly 100 includes a support member 104, such as a printed circuit board (PCB) substrate, having a first surface or side 108 (shown in FIG. 1), and an opposing second surface or side 112 (shown in FIG. 2). Support member 104 can be fabricated from any suitable PCB substrate. In the present embodiment, in which antenna assembly 100 is to be operated in the 60 GHz band, materials with attributes desirable for high-frequency operation are preferable, such as Megtron. Although antenna assembly 100 can be implemented with any suitable number of layers (that is, layers of conductive material, such as copper plating) and intervening dielectric layers, in the present embodiment support member 104 is a two-layer member, having conductive material on surfaces 108 and 112 (from which various elements of assembly 100 are fabricated, as will be discussed below), and a dielectric material separating surfaces 108 and 112.

Support member 104 includes a set of electrical contacts. In the present embodiment, as illustrated in FIG. 2, a pair of electrical contacts 200t and 200r are disposed on second surface 112 (e.g. etched from the copper layer on surface 112, the remainder of which may form a ground plane).

Antenna assembly 100 also includes an antenna 116 carried on first surface 108. Antenna 116, in the present embodiment, is etched from the copper (or other conductive material) layer of first surface 108. Antenna 116 includes a transmission element 120t connected to electrical contact 200t, and a reception element 120r connected to electrical contact 200r. Antenna elements 120t and 120r are collectively referred to as antenna elements 120 herein. As will now be apparent, in the present embodiment, in which contacts 200 are on the opposite side of support member 104 from antenna elements 120, antenna elements 120 are connected to contacts 200 by vias extending through support member 104 from surface 108 to surface 112.

As will also be apparent from FIG. 1, antenna elements 120 are patch antenna elements. Further, antenna 116 also includes parasitic patch elements in the form of at least one transmission parasitic element and at least one reception parasitic element. In the illustrated embodiment, two transmission parasitic elements 124t are disposed on opposite

sides of transmission element **120t**, and two reception parasitic elements **124r** are disposed on opposite sides of reception element **120r**.

Antenna **116** (that is, elements **120** and **124**) is of conventional design. That is, the size and spacing of the powered elements (**120t**, **120r**) and the parasitic elements (**124t**, **124r**) are selected according to any suitable parasitic patch antenna design available to those skilled in the art. Antenna assembly **100** also includes, however, several non-conventional structural features.

In addition to antenna **116**, antenna assembly **100** includes a conductive inner ring element **128** carried on first surface **108** and surrounding antenna **116**. In the present embodiment, conductive inner ring element **128** is etched from the same copper layer as antenna **116**. In other embodiments, when deposition is employed to manufacture support member **104**, antenna **116** and ring element **128**, ring element **128** can be deposited in the same deposition process as antenna **116**. Conductive ring element **128** is a copper element in the present embodiment, but can also be fabricated of any other suitable conductive material (e.g. gold or any other suitable conductive metal).

Conductive inner ring **128**, in the illustrated embodiment, continuously surrounds antenna **116**. In other embodiments, however, conductive inner ring **128** may include one or more breaks therein so as to substantially, but not entirely, surround antenna **116**. For example, conductive inner ring **128** may include breaks having a combined length of less than about ten percent of the length of the outer perimeter of conductive inner ring **128**.

Further, in the present embodiment, conductive inner ring **128** separately surrounds the transmission elements **120t**, **124t** and the reception elements **120r**, **124r** of antenna **116**. More specifically, conductive inner ring **128** includes a ring **132** encircling the entirety of antenna **116** (that is, surrounding both transmission and reception elements together). Conductive inner ring **128** also includes a divider **136** extending from a first side of ring **132** to a second, opposite side of ring **132**. Divider **136** extends between the transmission elements of antenna **116** and the reception elements of antenna **116**. Thus, transmission elements **120t** and **124t** are surrounded by divider **136** and a portion of ring **132**, while reception elements **120r** and **124r** and surrounded separately from the transmission elements by divider **136** and the remaining portion of ring **132**. In some embodiments, divider **136** can be omitted.

Antenna assembly **100** also includes a dielectric outer ring **140** mounted on first surface **108** and surrounding conductive inner ring **128** (and therefore also surrounding antenna **116**). Dielectric outer ring **140** is fabricated from any suitable dielectric material. Outer ring **140** can be fabricated from the same material as the substrate of support member **104** (e.g. Megtron), or from a different dielectric material. In the present embodiment, outer ring **140** is fabricated from a dielectric material without attributes desirable for high-frequency operation, such as FR4, due to the lower cost of such materials. While the high-frequency performance of the substrate material employed in support member **104** can impact the performance of antenna **116**, it has been determined that the high-frequency performance of the material employed for outer ring **140** has little or not impact on antenna performance.

Dielectric outer ring **140** can be manufactured separately from support member **104**, antenna **116** and inner ring **128**, and mounted on surface **108** using any suitable means (e.g. adhesive, heat bonding or a combination thereof). As best seen in FIG. 3, in the present embodiment, the inner perim-

eter of dielectric outer ring **140** is in contact with the outer perimeter of conductive inner ring **128**. In other embodiments, conductive inner ring **128** and dielectric outer ring **140** can be separated from each other on surface **108**.

Returning to FIG. 1, dielectric outer ring **140** is configured as a wall rising from surface **108** of support member **104**. In particular, dielectric outer ring **140** rises from surface **108** to a height greater than the height of the elements of antenna **116** and conductive inner ring **128**. By way of non-limiting example, in the present embodiment outer ring **140** has a height of about 0.5 mm, measured from surface **108**. Further, by way of non-limiting example, outer ring **140** has a width of about 2 mm, while inner ring **128** has a width of about 1 mm. As will now be apparent, the height of inner ring **128** above surface **108** is determined by the thickness of the metal layer on support member **104** from which inner ring **128** was etched. The height of inner ring **128** (and the elements of antenna **116**) is typically between 0.02 mm and 0.05 mm. As will be apparent to those skilled in the art, the height of antenna **116** elements and inner ring **128** is exaggerated in the drawings.

Although support member **104** and outer ring **140** are illustrated as having the same outer perimeters, in other embodiments, support member **104** can have a larger perimeter than outer ring **140**. In such embodiments, contacts **200r** and **200t** can also be placed on surface **108**, outside outer ring **140** (that is, so that outer ring **140** is between contacts **200** and antenna **116**). In such embodiments, contacts **200** are connected to antenna **116** by multiple vias (e.g. a via from antenna element **120t** to surface **112**, a trace along surface **112**, and another via back to surface **108**).

Referring to FIG. 3, antenna assembly **100** also includes a plurality of ground vias **300** connecting conductive inner ring **128** to the ground plane on surface **112**. The number and spacing of ground vias **300** is not particularly limited. For example, while only seventeen ground vias **300** are illustrated in FIG. 3, in some embodiments about one hundred ground vias **300** can be provided, either equally spaced along ring **132** and divider **136**, or spaced unequally.

As will be apparent, the transmission element **120t** of antenna **116** receives a signal delivered to antenna assembly **100** from processing hardware at contact **200t**, and emits radiation based on the signal. Reception element **120r** of antenna **116**, on the other hand, receives radiation and generates an output signal representing that radiation. The output signal is applied to contact **200r** for delivery to the processing hardware. Turning now to FIGS. 4A and 4B, examples of communications assemblies including both antenna assembly **100** and the above-mentioned processing hardware will be described.

FIGS. 4A and 4B depict cross-sectional views of wireless communications assemblies. In particular, FIG. 4A depicts a wireless communications assembly **400a** and FIG. 4B depicts a wireless communications assembly **400b**.

Each assembly **400** includes an assembly support member **404a**, **404b**, which in the present embodiment are four-layer PCBs. Each assembly **400** also includes a baseband processor **408a**, **408b** carried by support member **404a**, **404b** respectively. Baseband processors **408** are conventional baseband processors consisting of one or more integrated circuits mounted to assembly support members **404** by any suitable mounting technology (e.g. ball-grid array, or BGA).

Each assembly **400** also includes a radio processor **412a**, **412b**. Radio processors **412a** and **412b** are electrically connected to baseband processors **408a**, **408b**. However, as will be discussed below, the nature of the connection between radio and baseband processors varies between

assemblies 400a and 400b. In general, radio processors 412 receive incoming signals from antennas and transmit the processed incoming signals to baseband processors 408. Radio processors 412 also receive outgoing signals from baseband processors 408 and apply the outgoing signals to the antennas for transmission. To that end, each assembly 400 also includes an antenna assembly 100a, 100b. Antenna assemblies 100a and 100b are as described above, with certain exceptions set forth below.

Further, each assembly 400 includes a communications interface 416a, 416b connected to baseband processors 408a, 408b respectively (e.g. via traces and vias on assembly support members 404a, 404b). Communications interfaces 416 permit connection of assemblies 400 to a variety of computing devices and enable such computing devices to communicate using the wireless communication standard implemented by assemblies 400 (such as the WiGig standard). Communications interfaces 416 are, in the present embodiment, universal serial bus (USB) connectors. A wide variety of other interfaces may be employed, however, including other wired interfaces (e.g. Ethernet).

Turning to FIGS. 5A and 5B, assemblies 400a and 400b, respectively, are shown with antenna assemblies 100a and 100b omitted. As seen in FIGS. 5A and 5B, each assembly support member 404 also defines a mounting surface 500a, 500b thereon. Mounting surfaces 500a and 500b serve as locations to mount antenna assemblies 100a and 100b, respectively, to assemblies 400a and 400b. Antenna assemblies 100a and 100b can be mounted using any suitable technology, such as BGA.

Mounting surfaces 500a and 500b each include a set of host electrical contacts. Specifically, mounting surface 500a includes a pair of contacts 504r and 504t. As shown in FIG. 4A, when antenna assembly 100a is mounted to mounting surface 500a, contact 200t is electrically connected with contact 504t, and contact 200r is electrically connected with contact 504r. Radio processor 412a is mounted on an opposite side of support member 404a from antenna assembly 100a, and is electrically connected to contacts 504 (and therefore to antenna 116) by one or more vias 420.

Mounting surface 500b includes a pair of contacts 508r and 508t. Turning to FIG. 4B, radio processor 412b is mounted to support member 104 of antenna assembly 100b rather than directly to assembly support member 404b. Therefore contacts 200r and 200t are electrically connected to corresponding contacts on radio processor 412b. In order to electrically connect radio processor 412b to baseband processor 408b, antenna assembly 100b includes two additional, or auxiliary, sets of contacts: a first set that is electrically connected with contacts 508r and 508t when antenna assembly 100b is mounted to mounting surface 500b, and a second set that is electrically connected to additional contacts on radio processor 412b. Thus, a signal from baseband processor 408b are carried via suitable combinations of traces and vias in support member 404b to contact 508t (which may be implemented as multiple contacts in other embodiments). The signal is then transmitted, via support member 104 of antenna assembly 104b (and specifically via the two sets of additional contacts mentioned above), to radio processor 412b. Radio processor 412b then transmits the processed signal to antenna 116 (specifically, element 120t) via contact 200t.

Radiation received at antenna 116 is converted to a received signal and communicated to radio processor 412b via contact 200r. Radio processor 412b then performs any necessary processing of the signal and transmits the processing inbound signal to baseband processor 408b via the

second additional set of contacts mentioned above, followed by the first additional set of contacts and contact 508r.

As seen in FIGS. 4A and 4B, radio processors 412 and baseband processors 408 can be placed on the same side of support member 404 as antenna assemblies 100, or on the opposite side. In some implementations, particularly those with stringent size constraints, it may be preferable to place the antenna assembly on the side opposite the radio and baseband processors, to provide sufficient space for the antenna assembly's placement as well as for reduction of interference with antenna performance by other components.

Referring now to FIG. 6A, the gain achieved by an example implementation of antenna assembly 100 is illustrated in comparison to that of a conventional parasitic patch antenna (i.e. lacking inner ring 128 and outer ring 140). FIG. 6B, meanwhile, depicts a comparison of the level of mutual coupling experienced by the same example implementation of antenna assembly 100 with the level of mutual coupling experienced by the same conventional parasitic patch antenna. Mutual coupling refers to the undesired receipt, at the reception elements of the antenna, of transmitted signals generated by the transmission elements of the antenna. As seen in FIG. 6B, in the 60 GHz band antenna assembly 100 achieves either equal or lower levels of mutual coupling as those for the conventional antenna.

Various advantages to the assemblies discussed herein will now occur to those skilled in the art. For example, antenna assembly 100 may provide increased gain (over a conventional patch antenna) comparable with an antenna array, while avoiding at least some of the disadvantages of the array (e.g. complexity of manufacturing, mutual coupling, impedance bandwidth limitations).

The scope of the claims should not be limited by the embodiments set forth in the above examples, but should be given the broadest interpretation consistent with the description as a whole.

The invention claimed is:

1. An antenna assembly, comprising:
a support member having (i) a first surface, (ii) an opposing second surface configured to couple the antenna assembly to an antenna assembly support member, and (iii) a set of electrical contacts;
an antenna carried on the first surface of the support member and electrically connected to the set of electrical contacts, the antenna including (i) a powered element and (ii) a parasitic element;
a conductive inner ring element carried on the first surface and surrounding the antenna; and
a dielectric outer ring element mounted on the first surface and surrounding the conductive inner ring; wherein the dielectric outer ring has an inside perimeter that surrounds an outside perimeter of the conductive inner ring element.
2. The antenna assembly of claim 1, wherein the powered element includes:
a transmission element connected to a first of the set of electrical contacts; and
a reception element connected to a second of the set of electrical contacts.
3. The antenna assembly of claim 2, each of the transmission element and the reception element comprising a patch element.
4. The antenna assembly of claim 3, wherein the parasitic element includes:
a transmission parasitic patch element; and
a reception parasitic patch element.

5. The antenna assembly of claim 3, wherein the parasitic element includes:
- a pair of transmission parasitic patch elements disposed on opposite sides of the transmission element; and
  - a pair of reception parasitic patch elements disposed on opposite sides of the reception element.
6. The antenna assembly of claim 2, the conductive inner ring element continuously surrounding the antenna.
7. The antenna assembly of claim 2, the conductive inner ring element separately surrounding each of the transmission element and the reception element.
8. The antenna assembly of claim 2, the support member further comprising a ground plane; the conductive inner ring element connected to the ground plane by a plurality of ground vias.
9. The antenna assembly of claim 1, the dielectric outer ring element having an inner perimeter in contact with an outer perimeter of the conductive inner ring element.
10. The antenna assembly of claim 1, the support member comprising a first dielectric material.
11. The antenna assembly of claim 10, the dielectric outer ring element comprising a second dielectric material different from the first dielectric material.
12. The antenna assembly of claim 1, the dielectric outer ring element comprising a wall rising from the first surface of the support member.
13. The antenna assembly of claim 1, the set of electrical contacts disposed on the second surface of the support member.
14. A wireless communications assembly, comprising:
- an assembly support member carrying a baseband processor; the assembly support member defining a mounting surface including a set of host electrical contacts;
  - a communications interface carried by the assembly support member and connected with the baseband processor; and
- 35 an antenna assembly having:
- a support member having opposing first and second surfaces, and a set of electrical contacts, the second surface of the support member coupled to the mounting surface of the assembly support member;

- an antenna carried on the first surface of the support member and electrically connected to the set of electrical contacts, the antenna including (i) a powered element and (ii) a parasitic element;
- a conductive inner ring element carried on the first surface and surrounding the antenna; and
- a dielectric outer ring element mounted on the first surface and surrounding the conductive inner ring; wherein the dielectric outer ring has an inside perimeter that surrounds an outside perimeter of the conductive inner ring element.
15. The wireless communications assembly of claim 14, the host electrical contacts being electrically connected to the set of electrical contacts of the support member.
16. The wireless communications assembly of claim 15, further comprising:
- a radio processor connected to the baseband processor; wherein the set of host electrical contacts are electrically connected to the radio processor.
17. The wireless communications assembly of claim 16, the mounting surface defined on a first side of the assembly support member, and the baseband processor and the radio processor being supported on an opposing second side of the assembly support member.
18. The wireless communications assembly of claim 14, further comprising:
- the support member further comprising an auxiliary set of electrical contacts connected to the set of host electrical contacts;
  - a radio processor supported by the support member to connect the radio processor to the set of electrical contacts and the set of auxiliary electrical contacts.
19. The wireless communications assembly of claim 18, wherein the set of electrical contacts and the set of auxiliary electrical contacts are disposed on the second surface of the support member;
- the radio processor connected to the second surface of the support member.
20. The wireless communications assembly of claim 19, the baseband processor and the support member being connected to the same side of the assembly support member.
